UNITED STATES PATENT OFFICE.

WARREN L. JACKSON, OF JAMAICA, NEW YORK.

WRENCH.

SPECIFICATION forming part of Letters Patent No. 746,516, dated December 8, 1903.

Application filed May 2, 1903. Serial No. 155,363. (No model.)

To all whom it may concern:

Be it known that I, WARREN L. JACKSON, a citizen of the United States, residing at Jamaica, in the county of Queens and State of New York, have invented new and useful Improvements in Wrenches, of which the following is a specification.

My invention relates to wrenches; and the primary object of the same is to provide a device of this character in which the movable jaw thereof may have, after the same has been set to the size of a nut, automatically imparted thereto slight movements without interfering with the primary adjustment thereof to increase and diminish the distance between the rigid jaw and itself, whereby the engagement and disengagement of a nut is greatly facilitated.

Further objects of the invention will appear as the nature of the same is more fully understood from the accompanying drawings.

The invention consists in the construction, combination, and arrangement of parts hereinafter fully described and claimed, and illustrated in the accompanying drawings, showing the preferred form of my invention, and in which—

Figure 1 is a side elevation of a wrench constructed in accordance with my invention, the sliding jaw thereof being in section. Fig. 2 is a sectional view on the line 2 2, Fig. 1. Fig. 3 is a similar view on the line 3 3, Fig. 1. Fig. 4 is a perspective view of a fragmentary portion of the handle.

Referring to the drawings by reference-numerals, 1 designates the shank of the wrench; 2, a rigid jaw secured to the outer end thereof, and 3 a movable jaw slidably mounted thereon.

40 The jaw 3 is provided with a longitudinally-arranged slot 4, circular in cross-section and extending throughout the entire length thereof. This jaw is provided with a groove 5 at or near the inner end thereof communicating 45 with the slot 4 and in which is journaled a nut 6, the purpose of which will be herein-after described.

7 designates a rod having connection with the handle of the wrench, the free end of 50 which is adapted to pass through the nut 6 into the groove 4, the same being of a diameter smaller than the latter to permit of the ad-

justment of the jaw 3. The rod is provided with diametrically opposite screw-threads 8, which extend from a point at or near the top 55 to a point at or near the bottom thereof. This manner of threading the rod provides the same with two smooth and two threaded faces. The nut 6 is provided with a bore of a diameter greater than that of the rod through 60 which the bolt 8 is adapted to freely pass to facilitate the movement of the jaw 3. The nut at diametrically opposite points has the bore thereof provided with screw-threads 9, which in one position of the nut are adapted 65 to engage the threads 8 and secure the jaw 3 in its adjusted position, while in another position of the nut the threads 9 are disposed opposite the smooth faces of the bolt and between the threads 8, whereby the jaw 3 is 70 free to be adjusted upon the shank. The nut 6 is provided with an upwardly-projecting lip 10, through the medium of which the nut may be turned to either present the threads 9 opposite the smooth faces of the 75 bolt 8 or cause said threads to engage the threads 8.

10 designates the handle, which is provided with a bifurcated end 11, having alining perforations 12, through which passes to engage 80 the shank 1 and to fulcrum the handle thereon a bolt 13. The handle 10 through virtue of its fulcrum has a limited movement upon the shank, and as the jaw 4 is secured to the handle any movement of the latter will cause 85 the former to approach or recede from the jaw 2. The portion 11 of the handle has two vertically-disposed flanges 14, formed integral therewith and in which is formed alining and acutely-arranged elongated slots 15. 9c A bolt 16, which is carried by the rod 8, passes through the slots 15 to secure said rod to the handle. The connection of the rod 8 to the handle through virtue of the elongation of the slots 15 and their acute disposition permits of the handle having a movement upon the shank without materially interfering with the horizontal disposition of the rod, thereby obviating all liability of the mutilation of the threads 8 when the nut 6 100 is turned to lock the jaw 3 upon the rod.

The operation of the wrench may be explained as follows: The nut 6 is turned to place the threads 9 opposite the smooth faces

of rod 7, leaving the jaw free to be adjusted to the size of the particular nut, and then locked in such position by causing the threads 9 to engage the threads 8. The jaw 3 being locked to the rod 7 will follow any movement of the handle, the outward movement of which will cause said jaw to recede from the jaw 2, thereby increasing the distance between said jaws sufficiently to permit of the easy application of the wrench to the nut, while the inward movement of the handle causes the jaw 3 to approach the jaw 2, thereby consequently clamping the nut between the two jaws. The inward movement of the jaw is caused by turning a nut on or off a bolt, and the outward movement of the handle is caused when the wrench is applied to a nut by a reverse movement of the handle.

It is apparent from the above description, taken in connection with the accompanying drawings, that I provide a wrench which will greatly facilitate the engagement and disengagement of a nut by the wrench and that the same is cheap, durable, and efficient.

Having thus fully described the invention, what is claimed as new is—

A wrench comprising a shank provided with

a fixed jaw, a movable jaw mounted on the shank and provided with a through longitudinal slot, said jaw also being provided with a groove communicating with said slot and arranged at or near its inner end, a nut mounted in said groove and provided with oppositely-disposed screw-threads, a handle provided with a bifurcated end adapted to receive the end of the handle and provided with alining perforations, a bolt adapted to pass through the perforations and engage the shank to fulerum the handle thereon, vertically-disposed flanges formed integrally with the handle and provided with acutely-disposed, elongated slots, a bolt provided with oppositely-disposed screw-threads, said bolt having one of its ends fitted into the nut and its opposite end situated between the flanges, and a bolt arranged in the slots in the flanges and adapted to engage the threaded bolt.

In testimony whereof I affix my signature in presence of two witnesses.

WARREN L. JACKSON.
